UNITED STATES PATENT OFFICE.

HARVEY E. LEASURE, OF WILLIAMSBURG, IOWA.

BILL-HOLDER.

SPECIFICATION forming part of Letters Patent No. 380,685, dated April 10, 1888.

Application filed April 25, 1887. Serial No. 236,125. (No model.)

To all whom it may concern:

Be it known that I, HARVEY E. LEASURE, a citizen of the United States, residing at Williamsburg, in the county of Iowa and State of Iowa, have invented a new and useful Bill-Holding Machine, of which the following is a specification.

My invention relates to improvements in bill-holders in which two long brass-wire 10 hinges, one working with a spring, hold bills filed between two boards and give room for a varying number of bills and facilitate putting in and removing them, and provide easy reference to bill-heads by means of a hinged flap.

15 The objects of my improvements are, first, to provide a strong spring that is easily manipulated; second, to secure protection and easy access to bill-heads; third, durability in construction, and, fourth, to keep bills straight 20 in holder. I attain these objects by the mechanism illustrated in the accompanying drawings, in which—

Figure 1 is a top view of entire machine; Fig. 2, a sectional view of machine closed; Fig. 3, a sectional view of machine open for reception of bills and showing sectional view of spring; and Fig. 4 is a sectional view of machine closed, with flap drawn back.

The boards A and F are connected together 30 by the two wire hinge-arms C and D on either side of the holder, and which hold the boards parallel and keep the bills straight. The arm C has one bearing in the center of board A and a bearing in edge of lower board. The hinge-arm D has wide bearings b b on board A, to prevent the light hinge-arm from springing out of bearing in lower board by action of spring in opening and closing holder. The elevated hinge-rod c, between the two bear-

ings on board A, is connected with the double-acting spiral spring a, which bears on a stationary rod below. The flap B has two hinges, between which there is a lighter double-acting spiral spring, a', attached to a rod on flap and a stationary rod on board A. 40

45 By means of the lifting-ring E the holder is opened to position, as in Fig. 3, for the reception of bills, the double spiral spring stretching as it opens with an easy movement and contracting as the holder is closed with sufficient force to securely hold the bills between the boards. The spring on the flap has a similar action and contracts to hold the flap either open or shut.

50 I am aware that prior to my invention bill-holders have been made with stiff springs to securely hold the bills in place, but which rendered the holder difficult to open and close; that a flap with a rubber to secure it in place has been used in bill-heads, which necessitated holding the flap back while thumbing bills; 55 that the hinge-arms were provided with narrow bearings on cover, and that but one long wire hinge has been used to connect the boards together. I therefore do not claim such a combination, as herein set forth, broadly; but

60 What I do claim as my invention, and desire to secure by Letters Patent, is—

1. The combination, in a bill-holder, of the double spiral spring a with the central hinge, 70 substantially as set forth.

2. The combination, in a bill-holder, of the double-acting spiral spring a with the hinged flap B, substantially as described.

H. E. LEASURE.
